Des. 224,032

Patented June 27, 1972

224,032

HAY LOADING AND STACKING IMPLEMENT

Raymond A. Ade, Newton, Dean P. Brooks, Hesston,
and John D. Anderson, Canton, Kans., assignors to
Hesston Corporation, Hesston, Kans.

Filed Oct. 5, 1970, Ser. No. 25,339

Term of patent 14 years

Int. Cl. D15—03

U.S. Cl. D40—1

Fig. 2.

Fig.3.

Fig.4.

FIG. 1 is a perspective view showing the left side of a hay loading and stacking implement embodying the instant invention;

FIG. 2 is a perspective view showing the right side thereof;

FIG. 3 is a front perspective view thereof; and

FIG. 4 is a top, rear perspective view thereof.

We claim:

The ornamental design for a hay loading and stacking implement, as shown.
